DESIGN FOR A MIRROR

William B. Ligorner, New York, N. Y.

Application December 22, 1945, Serial No. 124,988

Term of patent 14 years

(Cl. D86—10)

To all whom it may concern:

Be it known that I, William B. Ligorner, a citizen of the United States, residing at New York, in the county of New York and State of New York, have invented a new, original, and ornamental Design for a Mirror, of which the following is a specification, reference being had to the accompanying drawing, forming a part thereof.

In the drawing:

Fig. 1 is a top plan view of a mirror in folded position, showing my new design;

Fig. 2 is a front perspective view of the same, showing a mirror in raised position;

Fig. 3 is a rear perspective view of the same, showing a mirror tilted to a different angle; and

Fig. 4 is a top plan view of Fig. 1, showing a mirror in fully opened position.

I claim:

The ornamental design for a mirror, as shown.

WILLIAM B. LIGORNER.
